GATE FOR ASH HOPPERS

Filed April 30, 1924

2 Sheets-Sheet 2

Fig. 2.

Fig. 3.

UNITED STATES PATENT OFFICE.

ROBERT H. BEAUMONT, OF PHILADELPHIA, PENNSYLVANIA, AND HARVEY MARETTE, OF EAST ORANGE, NEW JERSEY, ASSIGNORS TO BEAUMONT MANUFACTURING COMPANY, OF CAMDEN, NEW JERSEY, A CORPORATION OF NEW JERSEY.

GATE FOR ASH HOPPERS.

Application filed April 30, 1924. Serial No. 710,195.

To all whom it may concern:

Be it known that we, ROBERT H. BEAUMONT and HARVEY MARETTE, citizens of the United States, residing, respectively, in Philadelphia, Philadelphia County, Pennsylvania, and East Orange, Essex County, New Jersey, have invented certain Improvements in Gates for Ash Hoppers, of which the following is a specification.

10 One object of our invention is to provide means for carrying off the water used in quenching hot ashes in an ash hopper.

15 A further object of the invention is to provide a scraper, which removes the sludge from the gate as the gate is opened, the sludge passing into the wagon, or car, being loaded with ashes.

In the accompanying drawings:

20 Fig. 1 is a side view showing the ash hopper and the gate in section and illustrating our invention; Fig. 2 is a sectional view on the line 2—2, Fig. 1; Fig. 3 is a sectional plan view on the line 3—3, Fig. 2; illustrating the construction of the gate; and Fig. 4 is a detached, perspective view of the scraper.

25 Referring to the drawings, 1 is an ash hopper of the ordinary type. 2 is the base ring of the hopper. 3 is the fire brick lining. Depending from the base ring, in the present instance, are hangers 4 to which the rails 5 are attached. These rails may be attached to an overhead structure, independently of the hopper, if desired. 6 is a gate arranged to close the bottom of the hopper. The bottom 7 of the gate is solid and is inclined from the point α to the point γ and is provided with a raised lip 7^a. Mounted in the upper portion of the gate is a series 35 of longitudinally arranged grate bars 8. These grate bars are triangular, but they may be shaped differently without departing from the essential features of the invention. The grate bars are placed a sufficient distance apart to prevent the passage of the coarse ashes, but will allow the water used in quenching the ashes to pass into the hopper and with it a certain amount of fine ashes or sludge. After passing between the 45 grate bars, the water flows over the inclined

bottom of the gate, discharging at the end γ of the gate into a fixed trough 9, which is suspended from the ash hopper 1 by straps 10, the sludge being retained by the lip 7^a.

55 11 designates an outlet pipe that communicates with the gutter, leading the water to any convenient discharge point. The gate is provided with flanged wheels 12, which travel on the rails 5. Motion is imparted 60 to the gate by fluid under pressure in a cylinder 13, in which is a piston 14. This piston has a rod 15, which is attached to a bracket 16 in the gate, Fig. 1.

65 17 designates a scraper, which is located under the grate bars and is arranged to rest on the bottom 7 of the gate. The scraper has arms 18, which are pivoted at 19, to each side of the ash hopper, as shown clearly in Figs. 1 and 2.

70 It will be noticed in Fig. 1 that the scraper is set at an angle so that, when the gate is opened, it will accommodate itself to the inclined bottom and will remove any sludge that happens to pass between the 75 spaces of the grate bars. When the gate moves away from the gutter 9, the sludge is deposited, with the ashes, in the wagon, or car.

75 It will be seen by the above invention 80 that, when the ash hopper is loaded with ashes and is quenched with water, the water gradually seeps through the ashes and passes through the space between the grate bars. As the bottom of the gate is inclined, 85 the water flows into the fixed gutter at the front of the gate.

85 When the gate is opened to discharge 90 ashes from the hopper into a wagon, or car, the sludge that has been carried by the water past the grate bars and into the gate is removed from the gate by the fixed scraper and is discharged into the wagon, or car, with the ashes.

95 The grate bars are preferably arranged longitudinally of the gate so that they will slide more readily under the ashes when the gate is opened. Other types of grate bars may be used without departing from the spirit of the invention, and, in place of the 100

bars, a perforated plate, spaced bricks or other foraminous supports may be used to retain the ashes within the hopper and allow the quenching water to pass into the 5 gate.

We claim:

1. The combination of an ash hopper; a gate arranged to be located under the hopper; means for moving the gate into and 10 out of position; a series of grate bars on the gate; and a fixed gutter at the front of the gate, said gate being open at the front end to allow the water that is used in quenching the ashes to pass from the gate into the 15 gutter.

2. The combination of an ash hopper open at the bottom; a gate arranged to close the bottom of the hopper, said gate having an inclined bottom, the gate being open at one 20 end; and a series of grate bars at the upper portion of the gate, said bars being spaced a sufficient distance apart to allow the water used in quenching the ashes to pass into the gate and to flow to the open end thereof.

25 3. The combination of an ash hopper open at the bottom; a gate arranged to close the bottom of said hopper, said gate having a solid bottom; a grate in the upper portion of the gate; and a scraper arranged to remove any sludge that has passed the grate when the gate is opened.

35 4. The combination of an ash hopper open at the bottom; a gate for closing the ash hopper, said gate having a solid, inclined bottom; a series of grate bars in the upper portion of the gate spaced apart to allow the water that is used in quenching the ashes to pass into the body of the gate, said water carrying with it a certain amount of sludge 40 that accumulates in the bottom of the gate; and a scraper pivotally mounted on the

hopper and arranged to remove the sludge from the gate when the gate is opened.

5. The combination of an ash hopper open at the bottom; a fixed gutter at one end of 45 the hopper; rails under the hopper; a gate arranged to travel on the rails; means for moving the gate into the closed or the open position, the gate having a solid bottom, inclined towards the fixed gutter; a series 50 of longitudinally arranged grate bars mounted on the gate, the gate being open at one end so that the water that passes between the bars will flow into the gutter; and means for removing sludge that accumulates on the 55 bottom of the gate when the gate is opened.

6. The combination of a hopper open at the bottom; a gate arranged to move into and out of position in respect to the bottom of the hopper, said gate having a solid bottom; and a series of grate bars spaced apart 60 and arranged parallel to the line of movement of the gate, said gate having an outlet for the escape of water passing through the space between the grate bars.

65 7. The combination of an ash hopper; a gate arranged to be located under the hopper, said gate having a solid bottom provided with a lip at its outer end to retain sludge; a grate in the upper portion of the 70 gate; and a scraper arranged to remove sludge from the bottom of the gate as the gate is opened.

75 8. The combination of an ash hopper open at the bottom; a gate therefor; a foraminous support on the gate for the ashes; an outlet for the escape of water passing through the foraminous support; and means for moving the gate into and out of position.

ROBERT H. BEAUMONT.
HARVEY MARETTE.
